METHOD OF TRANSPORTING ASPHALTS
AND THE LIKE

William Henry Hampton, Berkeley, Calif., assignor to Standard Oil Company of California, San Francisco, Calif., a corporation of Delaware

No Drawing. Application March 28, 1934,
Serial No. 717,795

4 Claims. (Cl. 214—152)

This invention pertains to a new and advantageous method of commercially distributing asphalts and the like and relates more particularly to an improved method of transporting the higher melting asphalts in bulk form.

As is well known, a very large proportion of all the asphalt marketed at the present time in regions distant from the point of manufacture is packaged in either metal or wooden barrels or drums. This practice has long been recognized as being decidedly uneconomical and thoroughly unsatisfactory in a number of ways. The lack of economy in marketing a relatively low value product in containers which approach in cost the value of the contained product is quite obvious and becomes impressively so when, as is usually the case with asphalts, the containers are non-returnable. The cost of transferring packaged goods and especially barreled goods is always high as compared to bulk handling, while the space wastage in transport is also substantially at a maximum with barrel shaped packages.

Many and varied have been the attempts to find a method whereby the ever increasing volume of asphalt consumed could be distributed in bulk form, but each such proposal has encountered difficulties so considerable as to preclude adoption on more than a very limited scale under certain very specialized conditions in spite of the enormous potential savings possible to a really operable procedure.

The very hard natural asphalts and asphaltites have been shaped in coarsely broken or lump form similar to coal. This procedure has, however, been found impracticable when applied to the lower melting asphalts derived from petroleum.

The broad idea of dissolving asphalt in an appropriate solvent to give a fluid pumpable at ordinary temperatures has not proven feasible because of the cost of the solvent and/or the difficulties and expense of its removal with a satisfactory re-production of the original asphalt.

The practice of pumping even the lower melting asphalts in molten condition into and out of the bulk shipping container has, due to the very great difficulty of returning the asphalt to a molten condition at its destination, proven applicable to only a very limited extent when the bulk container to be used was a tank car or truck and never at all with larger containers such as tank ships.

I have now discovered that asphalts and particularly the higher melting asphalts may be produced in or converted to a form in which they may be transferred from vessel to vessel by ordi-

nary bulk fluid handling devices at ordinary temperatures.

My herein disclosed invention utilizes and extends this discovery to a general system of procedure whereby it now becomes possible in effect to transport any asphalt in bulk containers, any desired distance, with a facility and at an expense substantially identical with that involved in the transportation of an equal volume of an inherently fluid liquid such as water.

The broad object of this invention is to make available to the producer and to the consumer of asphalts the inherent economies of bulk transportation.

Another object of the invention is to provide a method whereby high melting asphalts and other solid hydrocarbons may be handled at ordinary temperatures by fluid handling devices.

Still another object of the invention is to provide a procedure by which regions remote from a source of supply of asphalts may be provided with a limited number of, usually two, bulk materials from which asphalts of a wide range of characteristics can be easily prepared to meet the exact requirements of the job in hand.

Further objects of the invention will be readily apparent from the description and discussion which follows.

In the general practice of producing asphalts from petroleum, the tar remaining after the more volatile constituents of the crude oil have been removed by distillation at atmospheric pressure is run to steam stills often operated under reduced pressure, whereupon distillation is continued until the bottoms remaining in the still possess the required physical properties, penetration, melting point, etc. The lower the penetration and the higher the melting point desired, the greater is the amount of distillate which it is necessary to take off. The residuum is then run from the still, while still hot, into containers for marketing, which, for local distribution, may consist of either heated and/or insulated tank cars or trucks, while for distant consumption, wooden or steel barrels are almost invariably used.

In the production of a very hard "A" grade asphalt having a melting point well above 200° F., which approaches the practical limit to which such distillation may be carried without cracking the residuum, asphalts of all lower melting points progressively exist in the still, commencing with the "E" grades of 80° F. or lower melting point and passing in order to "D", "C", "B" and finally

to "A" grades, as more and more of the distillable components are removed.

It is a fact, long recognized but little used, that if the distillate produced is going from any lower melting asphalt to one higher in the scale is collected separately, it may at any subsequent time be recombined with such higher member by simply heating the two together, in roughly the proportions in which they originally occurred, with the result that the lower melting asphalt may thus be re-produced with substantially its original properties.

I have now discovered that if a high melting asphalt such as the "B" or preferably the "A" grade is properly subdivided and properly sluiced, it may be pumped or blown and generally handled and transferred in bulk form by the usual types of fluid transferring equipment and may thus be transported in any desired type of bulk liquid containers.

For instance, if an "A" grade asphalt is run hot from the still through a properly constructed orifice plate into relatively cold water, it assumes the form of "shot" particles which, while tending 25 more or less toward a "tear-drop" form, retains the essential characteristics of spheres to the point that their suspensions in ordinary fluids such as water or air are readily handled by fluid means.

30 I have thus found that when asphaltic shot or tear-drops averaging from 2 to 5 millimeters in diameter are produced and admixed with sufficient water, usually more than 30% of their gross volume, a slurry results which may be pumped 35 by a centrifugal pump or transferred by other suction or blowing systems with a facility substantially equal to that possible in handling water alone.

Such a slurry may be pumped into and out of 40 the hold of a tank ship and since the shot in such condition shows little or no tendency to coalesce or stick together, particularly so long as the voids between particles remain substantially filled with water, a high melting asphalt in this form may 45 be stored for any desired time or shipped any desired distance with all of the advantages and economies inherent in bulk storage and shipment.

Since the higher melting "A" and "B" grades of asphalt are utilized in much smaller quantities 50 than the softer "C", "D" and "E" grades which comprise the bulk of the road building and general construction asphalts, the foregoing discovery will find its widest application in making possible the economical distribution of these softer 55 products. The shipment of a low melting asphalt by my method is, of course, indirect since it is not the low melting asphalt as such that is shipped, but rather the components from which it may be re-produced upon arrival at the point 60 of ultimate consumption.

My invention may be well understood by reference to the following specific example.

In the distillation of a typical California crude, if, when the contents of the still approximates a 65 300 penetration or "E" grade asphalt, the distillate passing over is segregated and collected until an "A" grade, approximately 220-240° F. melting point, residuum remains in the still, roughly 75% of distillate and 25% of asphalt, "A" grade, 70 will result. The "A" grade asphalt, having a specific gravity slightly greater than unity, may then be converted to shot by proper injection into water, as previously described, and will thus be in form for bulk shipment. The distillate, a 75 viscous liquid of viscosity about 1600 sec. Saybolt

universal at 130° F., may be shipped in bulk by the usual methods. Upon arrival at the point of consumption, this distillate is charged to the asphalt heating equipment which would ordinarily be employed in melting the finished asphalt shipped in conventional package form prior to use. It is heated to 350°-400° F. and the "A" grade shot, from which the water has been drained and/or blown as completely as possible, are slowly added. Upon striking the hot oil, the slight amount of water still adhering to the shot is flash vaporized and the hard asphalt will pass readily into solution and an "E" grade asphalt of more or less the same properties as that existing in the still at the time segregation of the distillate was started, will result.

In addition to the economies and convenience accruing from the bulk shipment of two such asphalt components, over the ordinary package shipment of finished asphalts, another advantage of almost equal magnitude results from my method of procedure in that the two components may be recombined in any desired proportions. Thus, an asphalt of any desired properties intermediate between the "E" grade existing 2 in the still at the start of segregating the distillate and the "A" grade actually shipped may be reproduced at the will and option of the consumer.

The extreme simplicity and convenience of a 3 method whereby a whole range of asphaltic products of a given type may be distributed through the economical bulk shipment of but two materials and its supreme flexibility so far as the consumer is concerned will readily be understood 3 and appreciated by those skilled in the art.

In general any asphalt, natural or prepared, steam refined or air blown, or in fact any similar hydrocarbon which is solid at normal temperatures may be transported in bulk entirely free 40 from all the disadvantages of package distribution by a proper application of the foregoing procedure. Asphalts or other products of less than about 170° F. melting point being handled by the two component method, while asphalts of 45 greater than about 170° F. melting point may be shipped directly in shot or other appropriate subdivided form.

While the shot form herein described will usually be found to be the easiest and most economical form of subdivision to produce as well as being most free flowing and having the least tendency to coalesce or agglomerate, under certain conditions it may be more desirable to adopt some other form such as ground or extruded 55 particles. The size of particles is likewise optional, being dependent upon the nature of the fluid handling means subsequently to be employed, rather than upon any principle of the broad method herein contemplated. Similarly, 60 while water will, for obvious reasons, usually constitute the fluid medium, other liquids and even other fluids such as air may, under certain conditions, be substituted. While it might occasionally be desirable to ship less water than necessary to fill the voids and with the higher melting products it might be found entirely practicable so to do it will, in general, be found to be good insurance against the highly undesirable results that would attend coalescence or agglomeration to keep the voids full of water or other similar liquid at all times.

In such application of this invention as contemplates the use of my two component method, the point at which collection of the distillate 75

should be begun will, in general, depend upon the softest grade of asphalt which it is desired to provide to a given region or locality.

Certain other modifications of the procedure herein described will be apparent to those skilled in the art and will be readily recognized as a part of my invention in its broadest scope.

Having now described my invention and the methods whereby it may be utilized to advantage, what I claim is:

1. The method of transporting to a region remote from the point of its production, an asphalt of melting point greater than about 170° F. which comprises the steps of pumping said asphalt in the form of free-flowing, shot-like particles of substantially uniform size and several millimeters in average diameter admixed with water into the hold of a tank ship, of maintaining said particles in said hold continually wet with water at substantially atmospheric temperature during transport and of finally pumping said asphalt particles, admixed with water, from said ship's hold at substantially atmospheric temperature.

2. The method of transporting asphalt as in claim 1, wherein the voids between asphalt particles are maintained full of water during transport.

3. A method for the bulk transportation of asphalt over long distances and in the absence of any solvent therefor, which comprises the steps of reducing asphalt of melting point above about 170° F. to free flowing shot-like particles of 2 to 5 millimeters average diameter, of transferring said particles by fluid handling means to a bulk container, of maintaining said particles in said container wet with an aqueous medium during transport and of subsequently removing said asphalt from said container by fluid handling means at substantially atmospheric temperature. 5

4. A method for the bulk transportation of asphalt as in claim 3 wherein the voids between particles are maintained substantially filled with 10 15 20 the aqueous medium.

WILLIAM HENRY HAMPTON.
